CLAIM

We claim the ornamental design for a rodent caricature pet bed, as shown and described.

DESCRIPTION

FIG. 1 is a perspective view of a rodent caricature pet bed showing our new design;

FIG. 2 is a front elevation view thereof;

FIG. 3 is a top plan view thereof;

FIG. 4 is a back elevation view thereof;

FIG. 5 is a left side elevation view thereof; and,

FIG. 6 is a bottom plan view thereof.
